CLAIM

The ornamental design for a replacement inner tube for tires, as shown and described.

DESCRIPTION

FIG. 1 is a side view of a replacement inner tube for tires showing my new design, the opposite side view being a mirror image thereof;

FIG. 2 is a front view thereof, the back view being a mirror image thereof;

FIG. 3 is a top view thereof;

FIG. 4 is a bottom view thereof; and,

FIG. 5 is a side view of an alternate configuration thereof.
